(57) **CLAIM**

The ornamental design for an indicator light as shown and described.

DESCRIPTION

FIG. 1 is an upper perspective view of an indicator light showing my new design;

FIG. 2 is a top plan view thereof; and

FIG. 3 is a front elevation view thereof, the rear, left and right sides being identical thereto.

FIG. 4 is an upper perspective view of a second embodiment of an indicator light showing my new design;

FIG. 5 is a top plan view thereof; and,

FIG. 6 is a front elevation view thereof, the rear, left and right sides being identical thereto.

The dot-dash circular lines in the various figures are boundary lines and form no part of the claimed design. The area circumscribed by the dot-dash circular lines is likewise not part of the claimed design. All other broken lines show environment for illustrative purposes only and form no part of the claimed design. Oblique line shading is used to show surfaces that are at least partially translucent.

The embodiments of FIGS. 1-3 and 4-6 are shown broken away to indicate unspecified length. The appearance of any portion of the article between the break lines forms no part of the claimed design.

1 Claim, 2 Drawing Sheets
